UNITED STATES PATENT OFFICE.

HENRY A. FRYE, OF NEW YORK, N. Y.

DESIGN FOR A LACE-FASTENING.

SPECIFICATION forming part of Design No. 31,843, dated November 14, 1899.

Application filed October 19, 1899. Serial No. 734,132. Term of patent 14 years.

To all whom it may concern:

Be it known that I, HENRY A. FRYE, a citizen of the United States, residing at New York city, in the county of New York and State of New York, have invented and produced a new and original Design for a Lace-Fastening, of which the following is a specification, reference being had to the accompanying drawing, forming part thereof, and in which the figure 10 is a perspective view of a lace-fastening, showing my new design.

The leading or material feature of my design consists in the design forming the subject-matter of the accompanying illustration.

15 The lace-fastening, which is especially intended for securing shoe-laces, has the top or crown A rounded transversely on its upper

side and provided with the slot B, leading from one end and having the flaring end B'. At its under side the top is drawn inward, 20 producing the downwardly-facing shoulders B², from which extend the depending legs C, which are shown as pointed and with their outlines simulating in side view the letter W.

Having described my invention, what I claim as new, and desire to secure by Letters Patent, is—

The design for a lace-fastening, as herein shown and described.

HENRY A. FRYE.
